US0D1040018S

(12) **United States Design Patent** (10) **Patent No.:** **US D1,040,018 S**
(45) **Date of Patent:** **** Aug. 27, 2024**

(54) **AERIAL VEHICLE**

(71) Applicant: **SZ DJI Technology Co., Ltd.**,
Shenzhen (CN)

(72) Inventors: **Shaojie Chen**, Shenzhen (CN); **Zhen Wang**, Shenzhen (CN); **Yun Zhao**, Shenzhen (CN); **Tao Peng**, Shenzhen (CN)

(73) Assignee: **SZ DJI Technology Co., Ltd.**,
Shenzhen (CN)

(**) Term: **15 Years**

(21) Appl. No.: **29/741,845**

(22) Filed: **Jul. 16, 2020**

Related U.S. Application Data

(63) Continuation of application No. 29/708,272, filed on Oct. 4, 2019, now Pat. No. Des. 907,558, which is a continuation of application No. 29/582,458, filed on Oct. 27, 2016, now Pat. No. Des. 862,359.

(57) **CLAIM**

The ornamental design for an aerial vehicle, as shown and described.

DESCRIPTION

FIG. 1 is a top front perspective view of an aerial vehicle showing the claimed design;

FIG. 2 is a bottom rear perspective view thereof;

FIG. 3 is a front view thereof;

FIG. 4 is a rear view thereof;

FIG. 5 is a left side view thereof;

FIG. 6 is a right side view thereof;

FIG. 7 is a top view thereof; and,

FIG. 8 is a bottom view thereof.

The broken lines in the figures show portions of the aerial vehicle that form no part of the claimed design.

1 Claim, 8 Drawing Sheets
